CLAIM

The ornamental design for a utensil, as shown and described herein.

DESCRIPTION

FIG. 1. is a perspective view of my utensil;

FIG. 2. is a front view thereof;

FIG. 3. is a rear view thereof;

FIG. 4. is a left side view thereof;

FIG. 5. is a right side view thereof;

FIG. 6. is a top view thereof; and,

FIG. 7. is a bottom view thereof.

Any broken lines in the drawings show environment that forms no part of the claimed design. Applicant makes no claim as to color with regards to the present invention.
